UNITED STATES PATENT OFFICE.

JACQUES MARETTE, OF VINCENNES, FRANCE, ASSIGNOR TO COMPAGNIE GENERALE DES ETABLISSEMENTS PATHÉ FRERES, PHONOGRAPHE ET CINEMATOGRAPHE, OF PARIS, FRANCE.

MACHINE FOR DEVELOPING AND FIXING CINEMATOGRAPHIC FILMS.

1,325,748.

Specification of Letters Patent. Patented Dec. 23, 1919.

Application filed May 19, 1914. Serial No. 839,505.

To all whom it may concern:

Be it known that I, JACQUES MARETTE, citizen of the Republic of France, residing at 30 Rue des Vignerons, Vincennes, Seine, in the Republic of France, have invented new and useful Improvements in Machines for Developing and Fixing Cinematographic Films, of which the following is a specification.

10 This invention relates to a machine for developing and fixing cinematographic films. This machine is particularly distinctive in that it comprises vertical vats of considerable height and circular or rectangular cross section, that respectively contain the various baths used for developing, rinsing, fixing, washing, coloring, toning, etc., these vats being arranged beside one another in the same plane and provided with the 20 nozzles required for obtaining a suitable circulation of the baths. The film which is to be developed and is wound off a reel is guided by mechanically controlled feed rollers and is lowered successively into the various vats while being kept stretched by heavy rollers that are suspended in equilibrium at the lower part of the loops formed by the film in the several vats. Devices for controlling the driving mechanism allow of regulating at will and in a very simple manner the duration of the immersion of the film in the developing bath.

In the accompanying drawings shown by way of example:

35 Figure 1 is a general diagrammatic view of a machine for developing and fixing arranged according to the invention.

Fig. 2 shows at a larger scale a part of the machine in sectional elevation.

40 Fig. 3 is a plan view of Fig. 2.

Fig. 4 shows another part of the machine in sectional elevation this part being adapted to be joined to the former part along the line A—A.

45 Fig. 5 is a plan view of Fig. 4 and is adapted to be joined along the line B—B of Fig. 3.

Figs. 6 and 7 together constitute an elevational view of the machine.

50 The machine shown by way of example in the accompanying drawings comprises a series of vertical vats juxtaposed in the same plane. These vertical vats may have a circular or a rectangular section and may be

made of metal, wood, glass or any other material, according to the nature of the bath they are to receive. 55

The machine shown comprises a series of vats or tubes numbered 1 to 8 and containing the developer, the latter being supplied at the lower part by a tube b and being made to flow out at the upper part through nozzles c. These vats are followed by two vats 9, 10 for rinsing, the water being made to run down, as shown, into the last tube 10 through which the film is passed, and being caused to flow up through tube 9. The film passes over a lantern N located between the vats 8 and 9 for observing the film and after passing through vats 9 and 10 goes through 70 a series of vats 11 containing hyposulfite supplied to the upper part of a pipe f, the film being subsequently passed through rinsing vats 12. Vats 12 are followed by a wiping device O and by vats 13 containing the 75 color baths for dyeing the film in a known manner.

The film M to be developed is contained in a magazine or box g and is guided on a series of rollers in such a manner that it is 80 passed down into each vat in the form of a loop. Two feed rollers h, i adjoining each vat are placed above the vat and the film is passed over these rollers. The film is kept stretched in each vat by a smooth roller k 85 provided with two cheeks that are sufficiently heavy to allow the roller to roll in equilibrium in the loop formed by the film and give the film sufficient tension in the bath, the roller being therefore much like the reel 90 of a diabolo game. The bottom roller k will as a rule and in its ordinary working position be in the lower part of the vat and will secure the transition of the film throughout the height of the vat without allowing the 95 film to wave. The time of immersion of the film in the bath contained in the vat will naturally depend on the level of this bottom roller.

If the vats are of opaque material they 100 comprise at their lower part glass sleeves such as m that have an adequate length and allow of observing the bottom rollers used as stretchers and determine their level at the moment the machine is started.

In the construction shown, the feed rollers provided at the top of the vat or tube 1 are toothed feeders i that are driven by a

longitudinal shaft o with the intervention of cross shafts n and bevel wheels. The longitudinal shaft o also drives by means of bevel wheels a smooth roller or guide roller h placed in advance of the first feed roller i , a smooth roller h which passes the film into the vat 2 and a toothed friction roller i^2 that may moreover be actuated directly by means of a friction crank p . The shaft driving the roller i^2 drives by means of a chain q the shaft of the smooth roller h of vat 3. By means of similar chain transmissions the toothed feed rollers i of tubes 3, 4, 5 and 6 drive the smooth rollers h of tubes 4, 5, 6 and 7 respectively. Shaft o is driven with the intervention of a clutch r by a shaft o^1 the latter being driven with the intervention of a clutch r^1 by a shaft o^2 . The shaft o^2 is driven with the intervention of a clutch r^2 by a shaft o^3 . Shaft o^3 is driven with the intervention of a clutch r^3 by shaft o^4 and o^4 is driven with the intervention of a clutch r^4 by a shaft o^5 . The clutches r to r^4 are controlled by levers H to H^4 on which springs I are made to act that tend to normally keep the clutches engaged.

By means of bevel wheels, shafts o^1 to o^5 are made to drive the toothed feed rollers of vats 3 to 7 respectively. Shaft o^5 moreover drives by means of bevel wheels the smooth roller h of vat 8, and this shaft is connected by means of gear wheels s , t , to an accessory or secondary shaft u and gear wheels v , w to a shaft x , which is driven directly by shaft z by means of bevel wheels y . Shaft z is driven by means of any suitable transmission. On the accessory shaft u , a gear wheel D is loosely mounted that can be geared with this shaft by means of a lever E and which engages with a gear wheel F keyed to a shaft G . The latter shaft G drives the toothed rollers i of vats 8, 9 and 10 as well as the smooth rollers h of vats 9 and 10 and one i^3 of the toothed rollers of vat 11, this roller being moreover provided with a driving friction crank J .

By means of bevel wheels shaft x drives the second toothed roller i of vat 11 and the toothed feed rollers of the other tubes 12 and 13 of the arrangement.

The working of the machine is as follows: The film to be developed is placed on a reel or spool that is stored in the magazine g and the film then passes in the direction of the arrow over the smooth feed roller h and over the first toothed roller i of the first vat, which roller i is driven in the manner described and secures the unwinding of the film. On having made a loop in vat 1 in which it carries a bottom roller h , the film passes over the second toothed roller i over the smooth roller h into vat 2 and then goes over the various rollers by successively passing down into the vats.

The film is thus submitted to the developing operation (in vats or tubes 1 to 8), the rinsing operation (in tubes 9 and 10), the fixing (in tubes 11), the rinsing (in tubes 12) and the dyeing (in tubes 13).

70

The duration of each operation is regulated:

(1) By the speed of the winding off of the film in the machine.

(2) By the number of tubes passed through in each operation.

(3) By the level of the bottom roller in each of the tubes.

The device described allows of varying the duration of the developing as follows: the immersion of the film is always complete in tubes 1 and 2, but its immersion can be varied in tubes 3 to 8. By operating one of the five levers H to H^4 , the part of the mechanism situated on the left of the disengaged lever can be stopped. If lever H^3 is disengaged for instance, as shown, the film is kept still in tubes 1 to 5 and as it continues to be drawn by roller i of tube 6 the bottom roller rises in this tube and the duration of immersion of the film in the developing bath contained in this tube diminishes. If on the contrary the bottom roller is to be lowered in this tube 6 so as to prolong the duration of the developing operation, it will merely be necessary, while keeping the lever H^3 disengaged, to turn the crank p in the direction of the movement of the rollers at a faster rate than the normal speed of the operation.

85

In order to submerge the film still farther in tube 8 it is merely necessary on the other hand to keep the lever E disengaged so as to keep shaft G at rest. The bottom roller is then lowered in tube 8. At the same time the duration of the immersion in the hyposulfite contained in tube 11 diminishes as the bottom roller of this tube is raised. This is however of secondary importance, as the number of tubes for fixing is always kept higher than is necessary. In order to diminish the duration of immersion in tube 8, it suffices to turn the crank handle J at a higher speed than the normal speed of the machine, while keeping lever E disengaged. This will have the subsidiary effect of increasing the duration of immersion in the fixing tube 11.

90

The invention is not restricted of course to the details of the arrangement shown and described, which has been chosen by way of an example.

105

Having now described my invention, what I claim as new and desire to secure by Letters Patent is:

1. A machine for developing and fixing cinematographic films comprising vertical vats juxtaposed in the same plane, means for supplying said vats with the various baths used for developing and the subsequent operations, means for continuously

110

120

driving the film and guiding the same so that it descends successively into each of the vats, said means embodying smooth feed rollers and toothed feed rollers arranged in the same horizontal plane above the vats, transversely arranged shafts, carrying said feed rollers, a longitudinal shaft divided into several sections, means for driving said shaft at one end, bevel gears connecting the various sections of the longitudinal shaft with the transverse shafts, clutches on said longitudinal shaft whereby various sections of the same may be disengaged and kept still and stretching means for the film in each vat, substantially as described and for the purpose set forth.

2. A machine for developing and fixing cinematographic films comprising vertical vats juxtaposed in the same plane, means for supplying said vats with the various baths used for developing and the subsequent operations, means for continuously driving the film and guiding the same so that it descends successively into each of the vats, said means embodying smooth feed rollers and toothed feed rollers arranged in the same horizontal plane above the vats, transversely arranged shafts, carrying said feed rollers, a longitudinal shaft divided into several sections, means for driving said shaft at one end, bevel gears connecting the various sections of the longitudinal shaft with the transverse shafts; clutches on said longitudinal shaft whereby various sections of the same may be disengaged and kept still, one section of said longitudinal shaft driving the feed roller which carries the film away from the last of the vats containing the developer and the next succeeding feed rollers up to that carrying the film into the first of the vats containing hyposulfite, inclusively, a secondary shaft coupling together the adjacent sections of the longitudinal shaft at both ends of the above sections, a clutch whereby said secondary shaft may be used at will for driving the above section, a friction crank whereby the feed roller which carries the film into the first of the hyposulfite containing vats may be driven at will at a speed faster than the normal speed, and stretching means for the film in each vat, substantially as described and for the purpose set forth.

In testimony whereof I have signed my name to this specification in the presence of two subscribing witnesses.

JACQUES MARETTE.
